UNITED STATES PATENT OFFICE.

JOSEPH L. OCHELTREE, JR., OF NORFOLK, VIRGINIA.

LOCKING DEVICE.

Application filed August 26, 1921. Serial No. 495,451.

To all whom it may concern:

Be it known that I, JOSEPH L. OCHELTREE, Jr., a citizen of the United States, residing at Norfolk, in the county of Norfolk and 5 State of Virginia, have invented a new and useful Locking Device, of which the following is a specification.

This invention is a locking device for securing caps to the radiators of automobiles, 10 and the like.

One of the objects of the invention is to provide means for preventing the loss of radiator caps and the like, by reason of the vibration concurrent with the travel of the 15 vehicle. A further object is to provide a device of the type mentioned, by means of which the unauthorized removal of the radiator cap, as by theft, is prevented, and the owner of the vehicle is protected against 20 the loss of any valuable accessory which may be secured to said cap.

The invention will be hereinafter fully set forth and particularly pointed out in the claims.

25 In the accompanying drawing:—

Figure 1 is a side view conventionally illustrating the invention as applied to an automobile radiator. Figure 2 is a plan view illustrating one of the locking collars 30 enlarged. Figure 3 is a transverse sectional view thereof. Figures 4 and 5 are plan and sectional views, respectively, illustrating a slight modification.

Referring to Figures 1, 2 and 3 of the 35 drawing, 10 and 10^a designate two collars, preferably of ovoid shape in plan view, each provided with an inner orifice. The shape of the collars, however, is immaterial. Passing diametrically through each collar 40 are threaded holes 11, and each collar is also provided with an opening 12, intersecting one of the threaded holes 11, and also intersecting another hole 13, leading in from the periphery of the collar and disposed in alignment with the last mentioned 45 hole 11. Working in the holes 11 are set screws 14, which project inwardly through the collars to engage the neck of the radiator C, and the radiator cap C', respectively.

In practice, when it is desired to apply the invention, the collar 10 is secured to the radiator C and the collar 10^a to the cap C'. In affixing the collar 10 in place, the set 55 screws 14 are first set flush with the inner orifice of the collar and the latter placed

around the neck of the radiator. Set screws 14 are then forced into engagement with said neck, thus securing the collar in position. The collar 10^a is secured to the cap 60 C' in a similar manner, in a position to bring said collar in contact with the collar 10. It will be noted that the hole 13 in each collar is so positioned that the screw 14 in alignment therewith, may be reached 65 by a suitable tool passed through said hole. When the collars have been secured in place the holes 12 are in register, so as to permit of the passage of the shackle of a padlock 15 therethrough. When the padlock is se- 70 cured in place, the shackle prevents access to those screws 14 which are in alignment with the holes 13, by inserting a screw driver or the like. Thus the radiator cap may not be removed without first disengag- 75 ing the lock 15, which will then permit of access to all of the screws 14.

In lieu of the constructions illustrated in Figures 1, 2 and 3, the form illustrated in Figures 4 and 5 may be employed for 80 preventing the unauthorized removal of the set screws or tampering with the fundamental parts which are vital to the protection required. Referring to said figures, 85 collars 16 and 16^a are provided with seg- mental recesses 17, to receive correspondingly shaped cover pieces 18, having countersunk holes 19, to accommodate screws 20, which are employed for securing the pieces 18 in place. Said recesses 17 are so 90 disposed as to intersect the holes 11 for the set screws 14, so that the heads of said screws are covered by said pieces 18, when the latter are in place.

The collar 16^a is provided with openings 95 21, to receive locking pawls 22, mounted upon guide posts 23, reciprocably mounted in the collar, and springs 24 are provided for forcing said pawls into complementary recesses formed in the collar 16. A retaining ring 25 is provided with suitable holes 26, to receive securing screws 27, by means of which said ring is secured to said collar 16^a, the movement of the pawls 22 being limited by said retaining ring. A suitable 100 key hole 28 is provided for insertion of a key to manipulate the locking pawls 22. In practice, the cap C' is removed from the radiator and the collar 16^a secured thereto. The collar 16 is also secured to the radiator 105 C while the cap is off. The cap is then screwed back to its position until the pawls

22 spring into the recesses in collar 16, and the two collars are then held against relative rotation, until the pawls are disengaged by means of a key.

- 5 The advantages of the invention will be readily understood. For instance, by placing the shackle of the padlock 15 so as to extend across the hole 13, it is impossible to remove all of the set screws without first 10 removing the lock, and substantially the same result is obtained by means of the segmental cover pieces 18. By locking the two collars together, relative rotation is prevented, and hence it is impossible to remove 15 the radiator cap without first unlocking or destroying the collars. An important advantage of the invention lies in the fact that the collars may be applied to any standard make of radiator without necessitating any 20 change in structure of the latter, or the use of additional attachments, and that said collars may be applied without marring the radiator or its cap.

It is obvious that instead of constructing 25 the collar 10^a or 16^a, as the case may be, independently of the cap C', the same may be made integral with the said cap, without departing from the spirit of the invention.

Having thus explained the nature of the 30 invention, and described an operative manner of constructing and using the same, although without attempting to set forth all of the forms in which it may be made, or all of the forms of its use, what is claimed is:—

35 1. A locking device of the character described comprising two complemental collars having inwardly projecting set screws, whereby said collars may be secured to two relatively rotatable members and means 40 whereby access to said screws is prevented when the collars are in operative positions.

2. A locking device of the character described comprising two complemental collars having means to engage two relatively 45 rotatable members, means for locking the collars together to prevent relative rotation, and means whereby disengagement of the collars from the parts to be protected is prevented while the collars are locked together.

50 3. A locking device of the character described comprising two complemental collars having inwardly projecting set screws,

whereby said collars may be secured to two relatively movable members, means for locking the collars together to prevent relative rotation, and means whereby access to the outer ends of the set screws is prevented when the collars are locked together.

4. A locking device of the character described comprising two complemental collars having inwardly projected set screws, whereby said collars may be secured to two relatively movable members, cover pieces for said set screws, and means for locking 65 the collars together to prevent relative rotation.

5. A locking device of the character described comprising two complemental collars provided with diametrically disposed 70 holes, recesses intersecting the outer ends of said holes, set screws working in said holes, cover pieces removably secured in said recesses, and means for locking the collars against relative rotation.

75 6. A locking device of the character described comprising two complemental collars having inwardly projected set screws, whereby said collars may be secured to two relatively movable members, a lock carried 80 by one collar, the other collar having recesses complementary to said lock, and means for covering the outer ends of said set screws.

80 7. A locking device of the character described comprising two complemental collars having diametrically disposed holes therein, and recesses intersecting the outer ends of said holes, set screws working in said holes, cover pieces removably secured in said recesses, and a lock carried by one 85 collar, the other collar having recesses complementary to said lock.

90 8. The combination with a radiator and a removable cap therefor, of a collar having inwardly projecting set screws engaging the 95 radiator, means carried by the cap complementary to said collar, means for locking said collar and said complementary means against relative rotation, and means whereby disengagement of the collar from the radiator is 100 prevented while said parts are locked against rotation.

In testimony whereof I have hereunto set my hand.

JOSEPH L. OCHELTREE, JR.
